UNITED STATES PATENT OFFICE.

MONROE GUETT, OF HARTFORD, CONNECTICUT, ASSIGNOR TO THE HART & HEGEMAN MANUFACTURING COMPANY, OF SAME PLACE.

ELECTRIC-SNAP-SWITCH COVER.

SPECIFICATION forming part of Letters Patent No. 660,633, dated October 30, 1900.

Application filed June 27, 1900. Serial No. 21,842. (No model.)

To all whom it may concern:

Be it known that I, MONROE GUETT, a citizen of the United States, residing at Hartford, in the county of Hartford and State of Connecticut, have invented certain new and useful Improvements in Electric-Snap-Switch Covers, of which the following is a specification.

This invention relates to those cup-shaped covers which are placed upon the bases of rotary snap-switches for inclosing the mechanisms.

The object of the invention is to provide a simple, inexpensive, easily-formed cover which has such characteristics as to eliminate all liability of short-circuiting current by the cover when the cover is upon or is being placed upon or being removed from the base.

The embodiment of the invention that is illustrated in the accompanying drawings consists of a cup-shaped exterior shell that is stamped to shape from sheet metal and a cup-shaped interior shell that is pressed from a single piece of peculiarly-blanked insulating paper.

Figure 1 of the views shows a plan of the blank of insulating-paper from which the interior shell is formed. Fig. 2 is a diametrical section of the interior shell that is pressed from the blank. Fig. 3 is a view looking into the interior shell. Fig. 4 is a diametrical section of the cover composed of the combined exterior metallic and interior insulating-shells, and Fig. 5 is a view looking into the completed cover.

The exterior shell of the cover is stamped from a single piece of thin sheet metal by a common punch and die, so as to form the circular top portion 1 and the annular side portion 2. A perforation 3 is made through the center of the top portion of the metallic shell. The blank 4 is cut from a sheet of paper or press board having the requisite insulating qualities and mechanical strength and pliability, with radially-projecting tongues 5 and a central perforation 6, that is slightly smaller in diameter than the perforation 3 through the metal shell. These tongues are formed by removing triangular pieces of material from between them, so that the opposite side edges of each tongue are parallel. The outer

edge of each tongue is a straight line extending at right angles to the side edges, and the apexes of the triangular openings 7, between the tongues, are in a circle having the diameter of the inside of the top of the cover. Each tongue is slightly longer than the width of the annular side portion 2 of the metallic shell. The blank thus cut from insulating-paper is laid upon the edges of the annular side portion of the metallic shell and then by the plunger of a suitable press forced down into the metallic shell until the circular portion 8 at the center lies against the inside of the circular top portion 1 of the metallic shell. When the insulating-blank is forced into the metallic shell, the tongues bend at right angles and their side edges meet, so that a cup-shaped shell is formed of the insulating material inside of the metallic shell.

The perforation through the top of the cover is provided for the switch-spindle, and the perforation through the metallic shell being slightly larger than the perforation through the insulating-shell it is impossible for the metallic shell to come into contact with the switch-spindle. As the tongues are somewhat longer than the width of the annular portion of the metallic shell the edge of the inner shell extends beyond the edge of the metallic shell, making it impossible for the metallic shell to be brought into contact with any of the switch parts when the cover is being placed upon or being removed from the base.

A cover formed according to this invention may be made with a thin exterior metallic shell which is cheaply manufactured and is capable of a high polish and decorative ornamentation, which thin metallic shell is strengthened by the interior shell, which has such rigidity that when forced into place it remains in position without the employment of any adhesive substance. Not only can the metallic shells of the covers formed in this manner be made of thin metal, but they are completely insulated, so that there is no danger of short-circuiting current through the switch parts by accidental contact when the cover is being placed in or being removed from position or by the gathering of moisture inside of the cover or by the contact with the

inside of the cover of the ends of the line-wires.

I claim as my invention—

1. A cover for a rotary snap-switch consisting of an exterior metallic shell having a circular top portion with a central perforation and an annular side portion, and an interior shell formed of sheet insulating material with a circular top portion having a central perforation and an annular side portion formed of integral tongues projecting from the central portion, the side edges of each tongue being parallel and the end edge of each tongue being at right angles with the side edges, substantially as specified.

2. A cover for a rotary snap-switch consisting of an exterior metallic shell having a circular top portion with a central perforation and an annular side portion, and an interior insulating-shell having a circular top portion with a central perforation that is smaller in diameter than the central perforation through the circular top portion of the metallic shell, and an annular portion that is wider than the annular portion of the metallic shell, substantially as specified.

MONROE GUETT.
